CLAIM

The ornamental design for a three-panel knock down shower screen as shown.

DESCRIPTION

FIG. 1 is a front elevational view of a three-panel knock down shower screen showing my new design;

FIG. 2 is a rear elevational view thereof;

FIG. 3 is a right side elevational view thereof;

FIG. 4 is a left side elevational view thereof;

FIG. 5 is a perspective view thereof; and,

FIG. 6 is another perspective view thereof.
